BEATER ROLL

Herbert T. Randall, Hamilton, Ohio, assignor to
The Champion Coated Paper Company, Ham-
ilton, Ohio, a corporation of Ohio

Application October 20, 1933, Serial No. 694,485

7 Claims. (Cl. 92—22)

This invention relates to beater rolls; and it comprises a beater roll of welded construction having in combination a shaft, a plurality of spaced discoid spiders mounted on the shaft, a plurality of arcuate flanges detachably mounted on the spiders, and a plurality of beater fly bars welded to the detachable flanges forming a unitary structure therewith, whereby a strong simple beater roll is produced allowing ready removal and replacement of the fly bars, and the space between the fly bars being left open, allowing free movement of pulp through the beater roll; all as more fully hereinafter set forth and as claimed.

A beating engine as used for processing fibrous pulp in paper manufacture generally comprises in combination an endless trough or the like, a metal bed plate mounted in the bottom of the trough, and a multi-bladed beater roll adapted to revolve in the trough adjacent the bed plate, the blades or fly bars of the beater roll clearing the bed plate a small fraction of an inch. In operation a charge of pulp in water suspension is placed in the engine, and is circulated around the trough by the roll. The rapidly revolving fly bars working in conjunction with the metal bed plate agitate and churn the pulp suspension, and hasten the hydration of the pulp fibers. In addition, some disintegration of the fibers takes place. Ordinarily the charge of pulp is circulated through the beating engine for several hours.

The beater roll runs at high speed, and the strains on it are severe. In order to insure rigidity the drive shaft is made extremely heavy; for a roll five feet in diameter the shaft is nine or ten inches in diameter. The fly bars must be securely mounted. A fly bar coming loose may wreck the roll and part of the beating engine.

The ordinary beater roll generally comprises separate fly bars or blades mounted on spiders carried on the shaft. A wide variety of clamping devices for securing the blades to the spiders has been proposed. Usually these devices make use of wedges in some way. In addition, it is customary to stiffen and strengthen the blades by driving wedge shaped filler pieces of wood between the bars. The wood swells when wet and holds the bars tightly. Although filling between the fly bars has long been accepted as a necessary feature of beater rolls, it has the disadvantage of forming pockets between successive fly bars in which pulp collects, reducing circulation and interfering with the normal beating. In addition, the wood fillers sometimes work loose. To overcome these objectionable features,

various designs of fly bars have been proposed.

According to the present invention I provide a beater roll in which the fly bars form practically a unitary structure with the spiders and the shaft, whereby possibility of a fly bar coming loose is eliminated. In addition, in my construction filling or bracing between the fly bars is dispensed with. This eliminates any pockets or dead ends where pulp might collect; and in addition allows free movement of pulp through the inter-blade spaces, which in turn allows a much faster circulation of pulp with the same expenditure of power. While securing these advantages, my beater roll construction nevertheless permits remarkably easy removal and replacement of the fly bars. I secure these advantages by making the fly bars integral with detachable flanges mounted on the spiders, by means of welding.

In the drawing I have shown, more or less diagrammatically, two modifications of a beater roll within my invention. In the showings,

Fig. 1 is a view partly in elevation, partly in vertical section, of one form of welded beater roll, a bed plate also being shown;

Fig. 2 is a partial view in vertical section taken at right angles to the view of Fig. 1;

Fig. 3 is a detail view showing the fly bars welded to the flanges;

Fig. 4 is a similar view taken at right angles to the view of Fig. 3; and

Fig. 5 is a view similar to Fig. 2 of a simplified form of beater roll.

In these showings, in which like reference characters indicate like parts throughout the several views, numeral 1 designates the shaft or spindle of the roll which is connected at one end to a source of power, not shown. The shaft is carried in bearings of usual form. Referring to Figs. 1 to 4, the shaft is provided with a plurality of hubs 2 by turning down the shaft to a slightly reduced diameter in the intervening spaces between the hubs. Each hub is provided with a collar 3 which is forced in position upon the hub by heavy pressure to prevent sidewise slipping of the collars. Each hub and collar is provided with a slot or key way into which the key 4 is driven to prevent rotational slippage on the shaft 1. 5 is a fly bar support, shown as a disk or spider welded to each collar 3. The shaft with the collars and disks constitute a strong, permanent durable support for mounting the replaceable beating elements. If desired, the spiders or disks may be welded directly to the shaft instead of using the collar construction described. Sometimes the spiders take the form of spoked wheels. Fig. 2

is a partial view of a roll and shows only two of the spiders. Usually four or five are employed in a roll.

The disks 5 are bored with a series of holes 6 near the periphery. On each disk are mounted two flanges 7 also bored with a series of holes 8 which are aligned with the holes 6 in the disks 5. Bolts 9 and nuts 10 securely hold the flanges to the disks 5. Flanges are used, instead of complete rings, in order to make possible the removal of each part from the beater when making replacements. The flanges are provided with a number of spaced slots 12 into which are fitted a plurality of fly bars 13. The fly bars are welded to the flanges by weld joints 14, forming a solid one-piece structure therewith.

It will be seen that the beater roll consists of a permanent structure comprising the shaft and spiders; and two replaceable units, comprising the flanges 7—7, carrying welded integrally therewith the fly bars 13. In the present example the fly bars are shown as welded to the flanges to form an integral unit, but, if desired, the flanges and fly bars may be cast together. In any case the fly bars and flanges form an integral structural unit without bolts, rivets or other clamping means. This structure avoids the use of complicated clamping devices for the bars, and wooden or metal filling between the fly bars. The beater roll is made entirely of metal. In addition, the structure provides free passage between the bars and the interior of the roll, whereby there is no possibility of the stock filling up in the spaces between the bars and interfering with beating and circulation. There are no pockets or dead ends; the roll is of open construction.

When it becomes necessary to replace worn fly bars, the nuts 10 are burned off with a torch, and the flanges, together with the fly bars 13, are lifted out bodily and replaced with new rings and bars. The shaft and the spiders are not disturbed. Long experience with beaters discloses very little necessity for replacing individual fly bars, because, when one bar becomes so worn or corroded as to require replacement, the other bars are usually in a similar condition. Replacement of a set of worn fly bars in the new roll is accomplished much more rapidly and cheaply than with the usual beater rolls.

The number of flanges is not restricted to two. Three or more may of course be used; but a set of two is convenient.

In certain types of beaters, such as for example breaker beaters, where the beater functions more like a disintegrator than a true beater, the wear on the fly bars is negligible, and in this case it is sometimes advantageous to dispense with the use of flanges and weld the beater bars directly to the spiders. In Fig. 5, I have shown a modified form of welded roll particularly useful in beaters of this type. As shown, the fly bars are here welded directly to the disks, forming an integral structure therewith. This construction gives an exceptionally strong roll, though of

course the fly bars are not readily replaceable as in the rolls shown in Figs. 1 to 4. In Fig. 5 the disks are shown as welded directly to the shaft. Here the entire roll including the shaft is a one-piece structure.

The beater roll in all its modifications is cheap and simple to construct and repair. Expensive and complicated blade locking devices are eliminated.

My welded beater roll presents several unexpected advantages when used in a beating engine.

In the case of an ordinary solid beater roll, having inter-blade spaces filled, the pulp charge must be "compressed", so to speak, in order to pass between the beater roll and the bed plate. The inter-blade spaces act as troughs. Air is trapped in them, compressed as the troughs pass the bed plate and then expanded again. In the present invention, the inter-blade spaces are clear. Hence when my roll is used in a beater engine there is no opportunity for air to become entrapped between the blades. Pulp circulates readily through the roll. The improvement in rate of circulation is substantial. Circulation with the new roll is much faster than in the case of wood-filled rolls, under identical conditions of power, stock, and speed of revolution.

What I claim is:—

1. A beater roll having a drive shaft and interior spaced means adapted to support fly bars, and a plurality of spaced fly bars integral with said means forming a unitary rigid self-supporting structure therewith and providing passage between the fly bars to the interior of the roll. 105

2. The roll of claim 1, wherein the supporting means comprise spiders carried by the shaft, and the fly bars are integral with the spiders.

3. The roll of claim 1, wherein the supporting means comprise spiders carried on the shaft and a plurality of flanges detachably mounted on the spiders, the fly bars being integral with the flanges. 115

4. The roll of claim 1, wherein the supporting means comprise spiders carried by the shaft, and the fly bars are welded to the spiders. 120

5. The roll of claim 1, wherein the supporting means comprise spiders carried on the shaft and a plurality of flanges detachably mounted on the spiders, the fly bars being welded to the flanges. 125

6. An improved, all-metal beater roll comprising in combination a drive shaft, a plurality of discoid spiders carried at spaced intervals on the shaft, a plurality of arcuate flanges for each spider, means for detachably mounting the flanges on the spiders, and a plurality of spaced fly bars integral with the flanges and forming a unitary structure therewith, so as to permit the flanges and fly bars to be removed from the spiders as units. 130

7. The roll of claim 6, wherein the fly bars are welded to the flanges.

HERBERT T. RANDALL.
